(73) Assignee: **Automatic Equipment Manufacturing Company**, Pender, NE (US)

(57) **CLAIM**

We claim the ornamental design for a double clevis connector for tow bar, as shown and described.

DESCRIPTION

FIG. 1 is a perspective top and side view of a double clevis connector for tow bar showing our new design;

FIG. 2 is a side elevational view thereof;

FIG. 3 is an elevational view showing the opposing side thereof;

FIG. 4 is a top plan view thereof;

FIG. 5 is a bottom plan view thereof;

FIG. 6 is an end elevational view thereof;

FIG. 7 is an elevational view showing the opposing end thereof; and,

FIG. 8 is a reduced side elevational view showing the double clevis connector for tow bar in use.

The broken line showing of details in FIGS. 1–8 is included for the purpose of showing environmental portions of the double-clevis connector for tow bar and forms no part of the claimed design.
